UNITED STATES PATENT OFFICE.

FRED CHENEY, OF DEVALL BLUFF, ARKANSAS, ASSIGNOR OF ONE-HALF TO J. M. McCLINTOCK, OF DEVALL BLUFF, ARKANSAS.

INSTRUMENT FOR HANDLING JEWELS.

1,305,881.

Specification of Letters Patent.

Patented June 3, 1919.

Application filed October 8, 1918. Serial No. 257,346.

To all whom it may concern:

Be it known that I, FRED CHENEY, a citizen of the United States, residing at Devall Bluff, in the county of Prairie and State of 5 Arkansas, have invented new and useful Improvements in Instruments for Handling Jewels, of which the following is a specification.

My present invention pertains to instruments for the use of jewelers; and it contemplates the provision of a peculiar and advantageous jewel container and setter, as hereinafter described and claimed.

In the accompanying drawings, hereby 15 made a part hereof:

Figure 1 is a side elevation of my novel instrument.

Fig. 2 is an enlarged longitudinal section of the same.

20 Figs. 3 and 4 are sections, taken in the planes indicated by the lines 3-3 and 4-4, respectively, of Fig. 1.

Figs. 5 and 6 are detail views of the retainer of the instrument.

25 Similar numerals of reference designate corresponding parts in all the views of the drawings.

Among other elements my novel device 30 comprises a cylindrical member 1, and a longitudinal central screw 2 bearing in the outer end of the cylinder 1 and having a head or finger piece 3. The screw 2 has for its function to move a follower-rod 4 that it carries forwardly as desired by the user.

35 The inner end of the cylinder 1 is open and is provided at diametrically opposite points with slots 5 for use in the connection of the container 6 to the tool formed by the cylinder 1 and screw 2. The cylinder 1 may be

40 made of any material compatible with its purpose, and the container 6 is preferably made of glass, though it may be of any other material without involving departure from certain of my claims. The container is pro-

45 vided at 7 with opposite lugs for coöperation with the slots 5 in the cylinder 1 in the connection of the container to the said cylinder. Manifestly the said connection may be readily effected, and while there is no liability

50 of casual disconnection yet when desired the container may be expeditiously and easily detached from the cylinder. In the container 6 is a longitudinal central bore 9, and

the follower-rod 4 extends into said bore to enable the device to properly handle super- 55 imposed jewels in the bore.

The jewels are held in place in the container 6 through the medium of a resilient retainer 10. The forward end of the container 6 is closed by the retainer stop 11, 60 said stop being carried by the body 12 which is split as shown and elastically clasps or embraces the container. The retainer 10 is preferably slotted at 13 to enable the operator to see the jewels in the container 6. 65

My invention contemplates the provision of a number of containers, and each of these will be provided with a label calculated to apprise a jeweler of the size and make and 70 class of movement of the jewels contained in the container. The invention also contemplates arranging the several containers in a cabinet, and the tool in a central compartment of the cabinet.

When the screw 2 is turned to force the 75 jewels downwardly in the container 6, the lowermost jewel will be about three-fourths exposed, see Fig. 5, and will be held firmly in place by the resilient retainer stop.

In practice my novel containers may obviously be manufactured so cheaply that it is feasible to use them for the storage and 80 shipment of jewels, and when this scheme is adopted my improvement will obviously enable a jeweler not only to expeditiously and 85 easily select the particular jewel that he desires to place, but will also enable the jeweler to manipulate and position the jewel without any liability whatever of the jewel being 90 chipped, scratched or otherwise marred. 90

It will also be appreciated that in the practice of my invention all of the jewels are safely preserved in a compact manner and so there is no liability of dust or other deleterious substance being deposited upon 95 the jewels.

In using my instrument the lowermost jewel therein is supplied with a drop of cement and is inserted in the hole in a roller table, and is pressed downwardly far enough 100 to enable the end portion 11 of the retainer 10 to touch the roller table. The jewel is then displaced from the container 6 by a slight movement of the screw 2, and when necessary the jewel is straightened in the 105 hole. Manifestly in this way the end desired

is attained without removal of the bow spring or the roller table.

When the container 6 is disconnected from the cylinder 1 of the tool, the jewels are held in the container by the end portion 11 of the container 6.

Having described my invention, what I claim and desire to secure by Letters Patent, is:

- 10 1. An instrument for the purpose described, comprising a cylinder, a screw bearing therein, a follower rod on the screw, a jewel container connected to the cylinder and having a bore for the reception of said rod and jewels, and a resilient retainer carried by the container and having an end portion opposed to the forward end of the container.
- 15 2. An instrument for the purpose described, comprising a cylinder having a bayonet slot, a screw bearing therein, a follower rod on the screw, a jewel container adapted to be disposed in the end of the cylinder and having a bore and also having a stud

movably engaging said bayonet slot, and a 25 resilient retainer clasping the container and having an end portion opposed to the forward end of the container.

3. The combination of a container for jewels having a longitudinal bore, and a resilient retainer clasping and carried by the container, and having an end portion opposed to the end thereof. 30

4. The combination of a container for jewels having a longitudinal bore, and a resilient retainer clasping and carried by the container and having an end portion opposed to the forward end of the container. 35

5. The combination of a transparent jewel container having a longitudinal bore, and a resilient retainer clasping and carried by the container and having an end portion opposed to the forward end of the container; said retainer being of open-work construction to display the jewels in the container. 40

In testimony whereof I affix my signature. 45

FRED CHENEY.
